UNITED STATES PATENT OFFICE

126,366

DESIGN FOR A VENDING MACHINE

Warren B. Green, New York, N. Y., assignor to U-Need-A-Pak Products Corp., Brooklyn, N. Y., a corporation of New York

Application December 11, 1940, Serial No. 97,252

Term of patent 14 years

To all whom it may concern:

Be it known that I, Warren B. Green, a citizen of the United States and a resident of the city, county, and State of New York, have invented a new, original, and ornamental Design for a Vending Machine, of which the following is a specification, reference being had to the accompanying drawings, forming part thereof.

I claim:

The ornamental design for a vending machine, substantially as shown.

WARREN B. GREEN.
